CAN EXTRACTOR

Ed Laxo, Oakland, Calif., assignor to Atlas Imperial Diesel Engine Co., Oakland, Calif., a corporation of Delaware

Application October 8, 1946, Serial No. 701,974

5 Claims. (Cl. 198—25)

1

The present invention relates to devices for extracting can bodies and the like from their conveying mechanism.

It is an object of the present invention to provide an improved and simplified device for disengaging or extracting can bodies from a conveying mechanism, such as a continuous strand roller chain carrying the can bodies in single file progression through one or a series of work performing stations.

Another object of the invention is to provide a can extracting or disengaging device which may be infinitely adjusted between limits to the closest degree, to insure accurate timing between the operation of the extractor device and the positions of the can bodies on the conveying mechanism.

A further object of the invention is to provide a device for extracting or disengaging can bodies from a conveying mechanism, whose proper operation remains unaffected by normal wear of the working parts.

One form which the invention may assume is exemplified in the following description and illustrated by way of example in the accompanying drawings, in which:

Fig. 1 is a fragmentary top plan view of a can body conveyor in operative relation to another chain conveyor to which the can bodies are to be transferred.

Fig. 2 is a top plan view of the can extracting or disengaging portion of the mechanism disclosed in Fig. 1, with its parts in can releasing position.

Fig. 3 is a section taken generally along the line 3—3 on Fig. 1.

Fig. 4 is a side elevation of the can extractor device as viewed from the right of Fig. 3.

As disclosed in the drawings, a conveyor chain 10 has gripping dogs 11 attached to certain of its links 12 at spaced intervals. These dogs are provided with slotted gripping portions 13 for holding individual can bodies 14 as they are conveyed through the machine, such as a mechanism for soldering the side seams of the can bodies. In the example of the invention disclosed in the drawings, it is proposed to release the can bodies from the gripping device 11 and transfer them at the proper time interval to a cooler chain conveyor 15 at the moment of turning of the gripper chain around a sprocket 16 whose teeth are drivably engaging the chain links.

The sprocket 16 is suitably attached, as by a key and slot connection 17, 18, to a vertical shaft 19 whose lower end is supported in suitable bear-

2

ings 20 mounted on the frame of the machine, and whose upper end is free of support to facilitate assembly and removal of certain parts of the can extractor or disengaging device.

5 A can extracting lever 21 is rotatably and oscillatably mounted on the shaft 19 above the sprocket, and is provided with oppositely disposed fingers 22, 22 adapted to engage the ends of the can bodies 14 and remove the latter from the link dogs 11. This lever is urged in a rearward direction with respect to the rotational direction of the sprocket by a tension spring 23, which has one end secured to a pin 24 attached to the lever 21 and its other end secured to a pin 15 25 fixed to the sprocket 16. A bearing pin 26 is fixed to the lever 21 (on the other side of the shaft from the pin 24) and carries a roller 27 engaging the biasing surface 28 on one end of an actuating lever 29, oscillatably mounted on a fulcrum pin or stud 30 secured to the sprocket, and provided with a cam follower roller 31 on its other end engageable with a stationary cam 32 in which the shaft 19 is rotatable.

10 The tension spring 23, through the intermediate diary of the extractor lever 21, holds the follower roller 31 constantly in engagement with the cam 32. This cam is held in fixed adjusted position by a holder rod 33 whose split larger hub end 34 embraces the cam hub 35 and is 15 clamped thereto in any suitable manner, as by a clamp screw 36 extending through the ears 37 of the rod. The outer end 38 of the rod is disposed over a fixed stud 39 to serve as an anchoring point, holding the rod 33 and the cam 32 20 clamped thereto stationary. A collar 40 is mounted on the shaft 19 in juxtaposed relation with the cam hub 35 and rod 33, and is fixed to the shaft by a set screw 41, in order to hold all 25 of the parts in proper assembled position.

20 In the example disclosed in the drawings, the extractor lever 21 is shaped to provide diametrically opposed can body engaging fingers 22, whose center of revolution coincides with the axis of the shaft. In the position shown in Fig. 1, one of 25 the fingers is about to extract or disengage a can body 14 from the conveyor chain gripper dog 11, to move it from the dog slot 13 and transfer it to the cooler chain 15. Since two diametrically opposed fingers are depicted in the drawings, the number of teeth in the sprocket 16 must be twice the number of chain pitches between successive gripper dogs 11 on the conveyor chain 10, in order that an extractor finger 22 is brought into can body end engaging position at each half 30 revolution of the sprocket.

It is further to be noted that two diametrically opposed lobes 42, 42 are formed on the stationary cam to oscillate the lever 29 twice during each revolution of the sprocket, and bias the extractor lever 21 to effect cam disengagement twice during each revolution of the sprocket. In addition to the two lobes 42, the cam has intermediate surfaces 43, 43 on its periphery which lie on a circle concentric with the axis of the shaft 19. Accordingly, as the sprocket 16 rotates with linear movement of the conveyor chain 10, the extractor lever 21 and actuating lever 29 are carried around with it, the roller 31 on the end of the actuating lever riding upon the periphery of the stationary cam 32. During the time that the follower roller is engaging each circular surface 43 of the cam, no oscillating movement is imparted to either the actuating lever or the extractor lever, and they revolve with the sprocket at the same angular speed, occupying rearward positions as influenced by the tension spring 23. However, as the roller 31 rides up one face 42a of each cam lobe 42, the roller end of the actuating lever 29 is moved outwardly to bias its other end 28 inwardly in a forward direction, and, through engagement of such end with the roller 27 on the extracting lever 21, imparts an additional angular movement in a forward direction to the extractor lever 21 and its fingers 22, causing the latter to engage the cam body ends and move them ahead of the gripper dogs 11 out of the dog slots 13, or to a position of freedom, allowing their transfer to the cooler chain 15 (see Fig. 2). As the lever roller 31 rides down the other face 42b of each cam lobe 42, the spring 23 returns the extractor and actuating levers 21, 29 to their original positions.

The cycle of operation is repeated as the cam roller 31 successively engages the cam lobes 42, each finger 22 successively engaging the ends of the can bodies 14 as they are fed in a forward direction by the conveyor 10, the spring 23 then returning the levers 21, 29 and fingers 22 to their initial positions. The position of the stationary cam 32 and its integral lobes 42 with respect to the follower roller 31 on the actuating lever 29 is preferably such that the can bodies 14 are removed or extracted from the gripper dogs 11 at the time the link 12 to which the dog is attached begins its turning movement around the sprocket 16. In the event that the time of contact of a finger 22 with the can body is to be varied, this can be done at will by loosening the clamping hub 34 of the holder rod 33 and turning the cam 32, either clockwise or counter-clockwise, as dictated by the requirements of the situation. Turning of the cam clockwise (as seen in Fig. 1) will advance the engagement of the fingers 22 with the cam bodies 14, and, conversely, its turning in a counter-clockwise direction will retard such moment of contact.

Although the device, as illustrated, has two extractor fingers 22 and two cam lobes 42, it is to be understood that the general operation of the device is unaltered through the use of only one finger or more than two fingers. As the number of fingers 22 is varied, the number of lobes 42 on the stationary cam must be varied correspondingly, and the ratio of the linear pitches between the position of the gripper dogs 11 on the conveyor chain 10 to the number of teeth in the sprocket 16 must also be correspondingly altered.

The entire unit is made compactly, with all parts readily accessible. The entire mechanism may be assembled by placing the parts on the

shaft 19 in the ascending order shown in Figs. 3 and 4, and the parts may also be removed by loosening the collar 40 and elevating the parts from the shaft in the reverse order to that in which assembly has occurred.

It is, accordingly, apparent that an extracting device has been provided in which infinite variation between certain fixed limits can be made in the instant of contact between the can body engaging fingers 22 and the can bodies 14. As normal wear occurs in the operating parts, the proper time of engagement of the can engaging fingers with the can bodies can be insured to offset the factor of wear. Such adjustment is readily performable in the manner described above through turning of only a single part, namely, the cam 32.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. Apparatus of the character described, comprising a conveyor chain having means located at spaced points thereon engageable with can bodies, a shaft, a sprocket for said chain secured to said shaft, a lever rotatable on said shaft for engaging and removing successive can bodies from said chain, an actuating lever pivoted on said sprocket and engageable with said lever, and a stationary cam around said shaft for moving said actuating lever on its pivot.

2. Apparatus of the character described, comprising a conveyor chain having means located at spaced points thereon engageable with can bodies, a shaft, a sprocket for said chain secured to said shaft, a lever rotatable on said shaft adjacent said sprocket for engaging and removing successive can bodies from said chain, an actuating lever pivoted on said sprocket and engageable with said lever, a stationary cam around said shaft adjacent said actuating lever for moving it on its pivot, and means secured to said shaft adjacent said cam to hold said cam, rotatable lever and sprocket in assembled relation on said shaft.

3. A sprocket assembly comprising a sprocket, a shaft concentric with and supporting said sprocket, a cam supported by said shaft and secured against rotation, said cam having a plurality of radial lobes, a main lever supported concentrically of said shaft and sprocket for rotation with said sprocket, said main lever having a plurality of radially disposed arms, an auxiliary lever supported pivotally and eccentrically on said sprocket and having a first arm engageable with said cam and a second arm engageable with said main lever and operable to pivot said lever on its fulcrum, and resilient means resiliently holding said main lever in contact with said second arm of said auxiliary lever and holding said first arm of said auxiliary lever in contact with said cam.

4. The sprocket assembly of claim 3 wherein said radial lobes of said cam are disposed equi-angularly about the axis of said shaft and said radially disposed arms of said main lever are equal in number to said lobes and are disposed equi-angularly about the axis of said shaft, and wherein said first arm of said auxiliary lever is provided with a roller as the means of engaging said cam.

5. A sprocket assembly comprising a sprocket, a shaft supporting said sprocket and concentric thereof, a cam having a plurality of radial lobes, said cam being supported by and concentrically of said shaft, means for securing said cam against rotation, a main lever supported by said shaft, having said shaft as its fulcrum and having a plurality of radial arms, said lobes and said arms being equal in number and being disposed equi-¹⁰ angularly about the axis of said shaft, an auxiliary lever secured to said sprocket for rotation therewith, having its fulcrum eccentric to said sprocket and having a first arm and a second arm, and spring means secured at one end to said

sprocket and at the other end to said main lever to hold said main lever in contact with said first arm and said second arm in contact with said cam.
